UNITED STATES PATENT OFFICE.

WALTER O. SNELLING, OF ALLENTOWN, PENNSYLVANIA, ASSIGNOR TO TROJAN POWDER COMPANY, OF NEW YORK, N. Y., A CORPORATION OF NEW YORK.

COAL-MINING EXPLOSIVE.

No Drawing.

Application filed October 30, 1924. Serial No. 746,873.

This invention relates to explosives and more particularly to improvements in explosives of the type employed in coal mining.

The principal object of the invention is to provide an explosive of this type having exceptional efficiency in the work for which it is primarily intended, and further to provide such an explosive having an extremely low flame temperature.

It is desirable for reasons of safety that any explosive employed in coal mining have a low flame temperature, and also that it be efficient in its coal-getting qualities and that it give a maximum of "prepared sizes", by which is meant coal in large lumps, or "chunky" coal in which a considerable percentage of the total material is represented by lumps of fair size. I have discovered that coal mining explosives possessing the aforesaid characteristics in exceptional degree may be prepared by adding hydrocellulose or its equivalent to mixtures of detonating substances such as nitrostarch, nitroglycerin, trinitrotoluene, or the like with inorganic oxidizing agents such as sodium nitrate, ammonium perchlorate, ammonium nitrate and similar oxygen-carrying salts.

The relative proportions of the constituents of the explosive may vary largely, but generally I prefer to use from 1% to 20% of hydrocellulose, in combination with 5% to 25% of nitrostarch, and 5% to 50% of ammonium nitrate or its equivalent.

As an example of an explosive constituting an embodiment of my invention, I may present the following:

	Per cent.
Nitrostarch	16.00
Ammonium nitrate	67.00
TNT	7.50
Sodium nitrate	4.00
Hydrocellulose	5.00
Zinc oxide	.20
Mineral oil	.30
	100.00

As indicative of the wide range of equivalents, I may, in the foregoing example, replace ammonium nitrate with guanidine nitrate or any like material; and in place of sodium nitrate, employ any suitable oxidizing agent such as potassium perchlorate, barium nitrate, or ammonium perchlorate.

Instead of zinc oxide, I may, for example, employ sodium bicarbonate.

Although an explosive made in accordance with the foregoing example and including nitrostarch will give extremely satisfactory results, the invention is not limited to this example nor to any of the individual ingredients thereof. Broadly the invention contemplates the use in a coal mining explosive of hydrocellulose or other hydroxylated body corresponding in chemical nature to hydrocellulose, but comprising hydrated or hydroxylated derivatives of other carbohydrates than cellulose, for the purpose of reducing the explosion temperature and increasing the coal-getting characteristics of the explosive. Obviously, the invention is applicable to coal mining explosives having a nitroglycerin, perchlorate, or any other explosive base.

As an example of such explosive, the following formula is given:

	Per cent.
Nitroglycerin	10
Ammonium nitrate	65
Sodium nitrate	5
Wood pulp	10
Hydrocellulose	5
Sodium chloride	4
Calcium carbonate	1
	85
	100

In an explosive of this type, it is possible advantageously to modify the wood pulp which normally is used as an absorbent for the nitroglycerin, so that this wood pulp is partially, but not wholly, transformed into hydrocellulose. This may be accomplished by treating the wood pulp with hydrochloric acid of insufficient strength to produce a high yield of hydrocellulose, or with stronger hydrochloric acid, but for an insufficient time to produce a high yield. Under these conditions, the wood pulp may be made to serve the double purpose of an absorbent of the nitroglycerin, and a highly efficient flame-deadening and temperature-reducing agent as well. The formula given may be modified accordingly, and in any other way within the range of equivalents.

I claim:

1. A detonating explosive comprising a detonating agent and hydrocellulose.
2. A detonating explosive comprising a

detonating agent, an oxidizing agent, and hydrocellulose.

3. A detonating explosive comprising a detonating agent and from 1% to 20% of hydrocellulose.

4. A coal mining explosive comprising nitrostarch and 1% to 20% of hydrocellulose.

5. A coal mining explosive comprising

5% to 25% nitrostarch, 5% to 50% of ammonium nitrate, and 1% to 20% hydrocellulose.

6. A nitrostarch explosive comprising hydrocellulose.

7. An explosive comprising nitrostarch, an oxidizing agent, and hydrocellulose.

WALTER O. SNELLING.
